UNITED STATES PATENT OFFICE.

CHARLES CAMPBELL WORTHINGTON, OF DUNNFIELD, NEW JERSEY.

DESIGN FOR A DUPLEX-STEAM-ENGINE FRAME.

SPECIFICATION forming part of Design No. 34,515, dated May 14, 1901.

Application filed June 18, 1900. Serial No. 20,773. Term of patent 14 years.

To all whom it may concern:

Be it known that I, CHARLES CAMPBELL WORTHINGTON, a citizen of the United States, residing at Dunnfield, county of Warren, and 5 State of New Jersey, have invented and produced a certain new and useful Design for a Duplex-Steam-Engine Frame, fully described and represented in the following specification and the accompanying drawings, forming 10 a part of the same.

This invention relates to a new and original design for a duplex-steam-engine frame; and the invention consists in the peculiar shape or configuration of the same, all substantially as shown in the accompanying drawings, in which—

Figure 1 is a side view of a duplex-steam-engine frame embodying the design. Fig. 2 is a plan view of the same. Fig. 3 is an end 20 view of the same looking to the right in Figs. 1 and 2.

The leading feature of the entire design for the steam-engine frame is its peculiar shape or

configuration, with the steam-chest portion A arranged above and centrally between the 25 cylinders and curving inwardly and downwardly to the steam-port portion B, from the base of which steam-port portion the steam-cylinders C curve outward and with the steam-cylinders developing into the cradle portions 30 D, which terminate in the end plate E. The cylinders C are shown as formed with flanges F at their outer ends, receiving the heads G, and with the supports H, by which the engine-frame is mounted on the base I, and the 35 usual piston and valve-rod stuffing-boxes K and valve-motion bracket L are shown.

What I claim is—

The design for a duplex-steam-engine frame, substantially as shown and described. 40

In testimony whereof I have hereunto set my hand this 13th day of June, 1900.

CHARLES CAMPBELL WORTHINGTON.
